UNITED STATES PATENT OFFICE

BOB LANSDON GALBRAITH, OF OLIVER SPRINGS, TENNESSEE.

SUSPENDERS.

Application filed August 13, 1924. Serial No. 731,880.

To all whom it may concern:

Be it known that I, BOB LANSDON GALBRAITH, a citizen of the United States, residing at Oliver Springs, in the county of

Anderson and State of Tennessee, have invented a new and useful Improvement in Suspenders, of which the following is a specification, reference being had to the accompanying drawing.

10 My invention relates particularly to suspenders used on overalls and similar garments having a bib or similar part reaching upward over the chest toward or to the shoulders.

15 The object of the invention is to provide suspenders adapted to be used on such garments and in which suspenders provision is made for protecting other garments and the shoulders of the wearer from injurious action by the buckles which are ordinarily applied to the front ends of said suspenders.

To this end, a sheet-form piece of material is applied to the inner side of the forward ends of the suspenders, as will appear fur-

ther on.

In the accompanying drawings,

Fig. 1 is a perspective showing the upper right hand corner of an overall bib with the forward end of a suspender embodying my improvement;

Fig. 2 is a front view of one end of one of the suspenders;

Fig. 3 is a side elevation of the structure shown by Fig. 2;

Fig. 4 is a longitudinal section on the line, 4-4, of Fig. 2, looking in the direction of the arrows, the part of the bib shown in Fig. 1 being added;

Fig. 5 illustrates the shield, the button loop and the yoke to which the shield is attached by stitching.

Referring to said drawings, A is the upper right hand corner of the bib of a pair of overalls or similar garment. A¹ is

45 any ordinary button secured on the front of the bib. A² is one member of a button-form snap. B is the body of the suspender. This body extends through the friction clasp, D, and downward through the slot of the upper

50 member, C, of the button loop and then extends upward and again through the friction clasp, D, and terminates at B¹, (Figs. 1 and 3). Two arms, C¹, extend downward

55 from the member, C, and have their lower ends coupled to the lower button loop member, C², which is in the form of an elongated

letter V and adapted to engage the button, A¹, by extending partially around the neck of the button between the button and the outer face of the bib, A.

The button loop is to be regarded as a form of buckle, and any similar buckle structure may be used in place of the particular form shown by the drawings. For convenience in description, the button loop structure may be called a buckle or buckle structure.

To prevent the button loop members from bearing on the shoulder of the wearer or upon the shoulder garment of the wearer,

the sheet-form shield, E, is applied behind or under the lower end of the suspender in position to bear upon the shoulder of the wearer. The upper end of the shield is se-

cured to the upper button loop or buckle member, C, by means of a yoke, F, and a loop, G. The yoke, F, has eyes, F¹, for en-

gaging the member, C. The loop shown by the drawings is in the form of a piece of cloth or other sheet-form material folded

around the yoke, F, and stitched or otherwise secured to the shield, E, far enough below the upper end of the shield to allow said end to extend above the button loop or buckle and overlap the lower or rear part of

the folded part of the body of the suspender, B, and be free from said body. The lower end of the shield extends downward behind the bib far enough to lie over the snap mem-

ber, A², and bear on its front face a com-

panion snap member, E¹, adapted to engage

the snap member, A².

In Fig. 5, the yoke is attached to the shield by stitching, F².

While the drawings show the shield about as wide as the body of the suspender, it is to be understood that the shield may be made wider.

It is to be observed that the shield does not interfere with the usual operation of the suspender nor with making usual adjustment of the length of the suspender.

The friction clasp may be of any form adapted to engage the body of the suspender in a manner permitting adjustment.

¹I claim as my invention,

1. The combination with the body of a suspender and the front upper part of an overall and a buckle structure for joining the suspender to said part of the overall, of a shield placed behind the buckle structure and overlapping and free from the lower

- part of the suspender body and extending behind the upper part of said part of the overall, means securing the shield to the upper part of the buckle structure, and 5 means for securing the lower part of the shield to said part of the overall, substantially as described.
2. The combination with the body of a suspender and the front upper part of an 10 overall and a buckle structure for joining the suspender to said part of the overall, of a shield placed behind the buckle structure and over-lapping and free from the lower part of the suspender body and the upper 15 part of said part of the overall, a yoke for securing the shield to the upper part of the buckle structure, and means for securing the lower part of the shield to said part of the overall, substantially as described.
- 20 3. The combination with the body of a suspender and the front upper part of an overall and a buckle structure for joining the suspender to said part of the overall, of a shield placed behind the buckle structure 25 and over-lapping the lower part of the suspender body and the upper part of said part of the overall, a yoke and loop for securing the shield to the upper part of the buckle structure, and means for securing 30 the lower part of the shield to said part of the overall, substantially as described.

4. The combination with the body of a

suspender and the front upper part of an overall and a buckle structure for joining the suspender to said part of the overall, of a shield placed behind the buckle structure and over-lapping the lower part of the suspender body and the upper part of said part of the overall, means securing the shield to the upper part of the buckle structure, means 35 on the overall for securing the buckle structure, and other means on the inner face of the overall for securing the lower part of the shield to said part of the overall, substantially as described.

5. The combination with the body of a suspender and the front upper part of an overall and a buckle structure for joining the suspender to said part of the overall, of a shield placed behind the buckle structure 40 and over-lapping the lower part of the suspender body and the upper part of said part of the overall, a yoke secured to the shield and having eyes for engaging the upper part 45 of the buckle structure, means for securing the buckle structure to said part of the overall, and means for securing the lower part of the shield to said part of the overall, substantially as described.

In testimony whereof I have signed my 50 name, this 29th day of July, in the year one thousand nine hundred and twenty-four.

BOB L. GALBRAITH.
